TWINE CONTROLLING AND CUTTING
DEVICE

Harvey Geroux, Los Angeles, Calif.

Application September 3, 1935, Serial No. 38,901

2 Claims. (Cl. 30—127)

This invention relates to a twine controlling and cutting device, applicable to flexible connections of different kinds and sizes, but more particularly intended for use in controlling and severing twine as it is being used to bind up packages of meat and other merchandise.

The invention is embodied in a simple, manually operable article adapted for effective use to guide a cord, to produce traction thereupon, and to sever such cord after the desired amount of tractive force has been applied thereto.

In the manual wrapping up of certain kinds of merchandise preparatory to delivery to customers, there has long been felt a need for some simple, inexpensive device to enable the salesman to draw twine or string tightly around the package without irritating his hands, and then expeditiously to sever the cord without having to stop to pick up a knife for that purpose.

20 The present invention provides a simple, inexpensive device to fulfil the aforesaid need.

Other objects, advantages and features of the invention may hereinafter appear.

Referring to the accompanying drawing, which 25 illustrates what is at present deemed to be a preferred embodiment of the invention,

Fig. 1 is a longitudinal vertical mid-section taken on line 1—1 of Fig. 2.

Fig. 2 is a top plan view.

30 Fig. 3 is a cross section taken on the irregular line 3—3 of Fig. 1.

Referring in detail to the drawing, the casing side plates 5 are alike in design but reverse in pattern, each preferably being of an arcuate character and having along its convex upper edge a flange 6 which abuts against its mate in the assembled article.

Each flange 6 is shown having near its front end an upwardly projecting ear 7 which, in the 40 assembly, abuts flatwise against one side of the knife K, a bolt 8, provided with a nut 9, extending through said ears and knife. Each casing plate 5 is also provided with a flange 10, which underlies the front portion of the plate and abuts 45 against its mate in the assembled article. At the rear end of the casing each flange 6 has a curved, downwardly directed portion 11, and a slot or open space 12 is left along the under edge of the device, which slot extends from the flange portions 11 to the flanges 10.

A front bolt or rivet 13 and rear bolt or rivet 14 cooperate with the upper bolt 8 to hold together the side plates of the casing, inwardly projecting apertured bosses 15 in an abutting 50 relation to each other, preferably being formed

at the place where the bolt or rivet 14 passes through the casing.

A manually operable, cord gripping lever 16, pivotally supported near its upper end upon the part 13, is mounted to swing within the casing 5 to and from a projecting position with relation to the slot 12. Said lever is normally yieldingly held in its projecting position by means of a leaf or wire spring 17 one end of which is fixed within a recess provided therefor in an upwardly 10 extending shoulder 18 with which lever 16 is provided.

The twine or cord 20 is led through the upper front part of the casing, entering through a rear opening 21 and emerging through a front opening 22, the upper portion of the lever 16 having a cord gripping surface 23 which, when said lever is manually retracted, cooperates with the opposite flanged portion of the casing to grip the cord firmly. The front portion of the knife K 20 is furnished with a cord cutting edge 24. The rear portion of the casing is shaped to form a handle, indicated by H in Fig. 1, somewhat like the handle of a pistol. The entire device need not be made as large or heavy as an ordinary 25 pistol, and may therefore be readily moved bodily into a position to cause the knife edge 24 to sever the cord while traction is being applied thereto.

The casing shown in the drawing forms a support for the cord gripping lever and for the knife K, which is externally mounted thereon. Any desired support or cord guide, within the scope of the appended claims, may be used without departing from the spirit of the invention.

Owing to the fact that the cord gripping surface or shoulder 23 of the lever 16 is much closer to its pivot 13 than is its handle portion, a moderate pressure of the fingers of the operator against the lower surface of said handle portion 40 will serve to grip the cord firmly. The handle portion of the device consists of an arcuate tube curved like the handle of a pistol, and the lever 16 is accessible to the fingers at the concave side of said tube.

45 In the operation of the device, the free end portion of a ball of twine, for example, is fed through the opening 21 and thence through the opening 22 whence it is extended sufficiently to be used in tying up a package. Thereupon, if for example, it is desired to tie a loop of cord around a bundle of merchandise which has previously been rolled into a cylindrical or other package form either with or without a wrapper, the cord 50 is first passed one or more times around the 55

bundle and then while the bundle lies upon a support the hand grasping the device is held at a sufficient distance from the bundle to permit the other hand to be used to tie the free end 5 portion of the cord into a slip knot about the run of the cord between the device and the bundle. After this has been done the looped cord with the slip knot therein is drawn tightly about the bundle by using the device to supply 10 traction thereupon with one hand while the other hand holds the bundle down. In this way a secure, tight loop of cord can be tied around the bundle, providing the slip knot made is of the kind that will not recede after the cutter of 15 the device has been used to sever the cord. Owing to the fact that the cord guiding means is confined to the front part of the elongated casing of the device, and is located at the side thereof opposite to the exposed portion 16 of the cord 20 gripping lever, the part of the cord being used, and also the adjacent supply portion thereof, is kept out in front of the hand of the operator, and in clear view, thus minimizing the danger of the cord becoming entangled.

25 I claim:

1. In a device of the kind described, a casing having a knife mounted externally thereon and a cord guide leading therethrough, and furnished with a handle portion whereby said casing is manually bodily movable to sever said cord, and means within said casing to grip the portion of the cord within the casing between said means and said casing, said cord gripping means comprising a pivoted lever operable by the fingers of a hand which is gripping said handle portion, 5 the cord-gripping portion of said lever being near its pivot and the portion thereof engageable by the fingers of the operator being remote therefrom, there being an opening for the cord through the wall of the casing adjacent to said 10 knife in order that the cord may be directed backwardly from said opening and then severed by said knife while said cord is held under tension by said cord-gripping means. 15

2. The subject matter of claim 1 and, said 20 handle portion being of an arcuately tubular character, and said cord-gripping lever being accessible for operation by the fingers at the concave side of said handle portion.

HARVEY GEROUX. 25
